[57] CLAIM

The ornamental design for a ski rack, substantially as shown and described.

DESCRIPTION

FIG. 1 is a front elevational view of a ski rack showing my new design, the rear being unornamented, the skis being shown in broken lines for illustrative purposes only;

FIG. 2 is a top plan view thereof;

FIG. 3 is a bottom plan view thereof;

FIG. 4 is a side elevational view taken from the right of FIG. 1, the side opposite being a mirror image thereof, again the skis and portion of a wall being shown in broken lines for illustrative purposes only.
